UNITED STATES PATENT OFFICE

107,962

DESIGN FOR A SHOE

Josef Lanz, Salzburg, Austria, assignor to The
Stetson Shoe Company, Inc., Weymouth, Mass.,
a corporation of Massachusetts

Application September 25, 1937, Serial No. 71,798

Term of patent 3½ years

To all whom it may concern:

Be it known that I, Josef Lanz, a citizen of Austria, and a resident of Salzburg, Province of Salzburg, Austria, have invented a new, original, and ornamental Design for Shoes, of which the following is a specification, reference being had to the accompanying drawing, forming a part thereof.

In the drawing:

Fig. 1 is a plan view,

Fig. 2, a side elevation, and

Fig. 3, a front elevation of a shoe showing my new design.

The essential features of my design for a shoe of the Romeo type include the close proximity of the rear edges of the vamp to the forward edges of the counter, the resulting narrow, upwardly diverging, V-shaped spaces separating these edges, and the ornamental bellows folds occupying these spaces.

I claim:

The ornamental design for a shoe, substantially as shown and described.

JOSEF LANZ.
